UNITED STATES PATENT OFFICE.

CHARLES H. FULLER, OF PORTLAND, OREGON, ASSIGNOR TO FULLER DAVIT COMPANY, OF PORTLAND, OREGON, A CORPORATION OF OREGON.

BOAT-LAUNCHING APPARATUS.

1,339,647.

Specification of Letters Patent. Patented May 11, 1920.

Application filed June 30, 1916. Serial No. 106,989.

To all whom it may concern:

Be it known that I, CHARLES H. FULLER, a citizen of the United States, and a resident of the city of Portland, county of Multnomah, State of Oregon, have invented a certain new and useful Improvement in Boat-Launching Apparatus, of which the following is a specification.

This invention relates generally to boat launching apparatus of the class commonly used by ships for launching life-boats.

Many sea disasters have resulted from insufficient working of life-boat launching apparatus, and one of the main objects of my invention is to provide an improved form of this class of apparatus which will work more efficiently than others hitherto promulgated.

To accomplish this object of my invention I provide an apparatus which will be capable of simple operation, which will be built of few parts, and contain no sensitive mechanism.

In the accompanying drawings:

Figure 1 is an elevation of the right end of the boat launching apparatus as viewed from inboard;

Fig. 2 is a sectional detail of the reversing gear mechanism; and

Fig. 3 is a left-end elevation of the parts shown in Fig. 1, the broken lines indicating a movement of the davit arms.

a represents the deck of a ship on which my apparatus is mounted. The opposite ends of the apparatus are similar, so I shall describe only one end, as illustrated in the drawings.

b, c are parallel standards rigidly mounted on the deck, said standards being braced by the transverse members *d*. The inner standard *b* has rigidly mounted thereon a vertical channel-iron post *e*, which is provided on its upper end with a cap *f*, which forms a bearing for the free running fair-leader sheaves *g, h*. The sheaves *g* are rotatable in a vertical plane longitudinal with respect to the boat, and the sheaves *h* rotate in a transverse vertical plane. A shaft *i* is rigidly mounted in bearings *j*, on the upper ends of the standards, and a fair-leader sheave *k* runs loosely on and along said shaft. A shaft *l* is also rigidly mounted between the standards, parallel and in the same vertical plane with the shaft *i*. A winding drum *m* is rotatably mounted on

the shaft *l*, and is adapted to wind and unwind the boat-fall *n*, which runs over the fair-leader sheaves *k, g, h*. Said drum is provided with an integral spur-gear *o*, which is driven through a gear train, as follows: A rotatable shaft *p* has fixed thereon a spur gear *q*, and one end of said shaft is adapted to receive a crank handle *r*. A second rotatable shaft *s* has fixed thereon the spur gears *t, u*, a ratchet *v* and brake drum *w*. The gear *t* is in engagement with and driven by the gear *q*, and the gear *u* is in engagement with and adapted to drive the gear *o*. A gravity pawl *x* cooperates with the ratchet *v* so as to normally lock the shaft *s*, and thus the drum *m*, against unwinding. A brake-lever is indicated by *y* and a brake band by *z*, and said brake is adapted to control the unwinding of the drum when the pawl and ratchet lock is disengaged.

A worm-gear segment 2 is rotatably mounted on the projecting end of the shaft *l*, and carries a rigid davit arm 3, braced by tension rods 21. The davit arm 3 has on its outer end a cap 4, which forms a bearing for free running fair-leader sheaves 5, which are rotatable in the plane of the sheaves *h*.

A life-boat is represented by 6, and the boat-falls *n* connect the boat with the winding drums *m*, as indicated in the drawings. With this arrangement of fair-leaders, the boat-falls will never foul regardless of the positions of the davit arms.

A worm 7 is fixed on a shaft 8, which is mounted in bearings 9 on the side of the standard *b*. Said shaft has also fixed thereon a bevel gear 10. A hollow shaft 11 is rotatably mounted between the standards *b, c*. A spur gear 12, fixed on said shaft, is in engagement with and driven by the gear *t*. Reversing bevel gears 13 are loosely mounted on a projecting end of the shaft 11. The bevel gears 13 are provided on their opposed sides with square-jaw clutch-faces 14, and a clutch sleeve 15, longitudinally movable between the gears 13, is adapted to be engaged with either one of said gears. The hollow shaft 11 is slotted, as indicated by 16 in Fig. 2, and a solid shaft 17, longitudinally and rotatably mounted in the hollow shaft 11, is provided with a pin 18, which extends through the slots 16 and the clutch sleeve 15. The outer end of the shaft 17 is provided

with a swivel head 19, which is pivoted to a shifting lever 20. Operation of this lever will place the reversing gear in neutral or in either of its active positions.

5 The general operation of my device is as follows:

By means of the shifting lever 20, the 10 clutches controlling the bevel-gears 13 may be positioned for placing either of said bevel-gears into operative contact with bevel-gear 10 on the shaft of the worm 7, for swinging the davit-arms in either direction. When said clutch is placed in its neutral position, the davit-arms will be held in 15 the position in which they are at the time. In launching life-boats, the davit arms are first swung inboard to the proper position over the boat, and the falls fastened to the latter. The boat is then elevated and the 20 davit arms swung outboard till the life-boat clears the side of the ship. The position to which the arms are swung will depend upon the list of the ship. The gear connections are so sized that when the davit arms 25 are swung inboard or outboard, boat-falls will wind or unwind, so as to cause the life-boat to travel in substantially a horizontal plane.

The reverse operation of my device, in 30 shipping a boat, is obvious.

I claim:

1. In a boat launching apparatus of the character described, parallel segment gears rotatable on a horizontal axis, davit-arms 35 carried by such gears, means for controlling

the rotation of said davit-arms through the medium of said gears, sheaves carried by the free-ends of said davit-arms, rotating in a plane transverse to the axis of rotation of said davit-arms, a fixed post adjacent each 40 davit-arm, sheaves at the top of the post, such sheaves rotating in the same plane as the sheaves carried by the davit-arms and overlying the latter sheaves, a winding drum, boat-falls winding thereon, means 45 for guiding the boat-falls over the top of said posts and to said sheaves carried by the latter, and means for rotating said drums.

2. In a boat launching apparatus of the character described, parallel segment gears 50 rotatable on a horizontal axis, davit-arms, carried by such gears, means for controlling the rotation of said davit-arms through the medium of said gears, sheaves carried by the free-ends of said davit-arms, rotating in 55 a plane transverse to the axis of rotation of said davit-arms, a fixed post adjacent each davit-arm, sheaves at the top of the post, such sheaves rotating in the same plane as the sheaves carried by the davit-arms and 60 overlying the latter sheaves, a winding drum, boat-falls winding thereon, means for guiding the boat-falls over the tops of said posts and to said sheaves carried by the latter, means for rotating said drums, and 65 connections between the latter means and the means for controlling the rotation of said davit-arms.

CHARLES H. FULLER.
